UNITED STATES PATENT OFFICE.

ARISTARCHUS F. HUBBARD, OF SIMMLER, CALIFORNIA.

AIR-SHIP.

SPECIFICATION forming part of Letters Patent No. 668,375, dated February 19, 1901.

Application filed August 11, 1898. Serial No. 688,353. (No model.)

To all whom it may concern.

Be it known that I, ARISTARCHUS F. HUBBARD, of Simmler, in the county of San Luis Obispo and State of California, have invented a new and Improved Air-Ship, of which the following is a full, clear, and exact description.

My invention relates to an improvement in flying-machines, and comprises the novel features hereinafter described and claimed.

Reference is to be had to the accompanying drawings, forming a part of this specification, in which similar characters of reference indicate corresponding parts in all the figures.

Figure 1 is a side elevation and partial section of my device. Fig. 2 is a top plan view with the body partially in section, and Fig. 3 is a detail showing in section the pivotal connection of the frames carrying the propeller mechanisms with the body of the air-ship.

A suitable body or house is constructed, the upper portion of which forms a gas-containing chamber A', which acts as a balloon to support the major portion of the weight in the air. This chamber may be made of such a size and material as is found to be best adapted to the purpose. It may in some cases be relied upon to supply the greater part of the lifting power and in other cases only a small part, the remainder being supplied by the mechanism installed in the lower compartments. Beneath this floating chamber is a chamber A, which contains the machinery for operating the air-ship, together with the passengers and freight. Extending through the lower chamber are two transverse and horizontal shafts B. I have herein shown only two shafts, although a greater number may be used, if desired. These shafts project beyond the sides of the body of the ship and are adapted for connection with the propellers, by which the raising and lowering of the ship and its propelling are effected.

Where the shafts pass through the side walls of the body, they are surrounded with sleeves C'. (Shown in detail in Fig. 3.) These sleeves are again mounted in bearings a, which are secured to the body of the ship. To the outer ends of the sleeves C' are secured rings C, within which are secured propeller-wheels P. These propeller-wheels are mounted upon vertical shafts, which are secured in

suitable bearings carried by the ring C, said bearings being supported in cross-bars P'.

Upon the vertical shaft of the propeller-wheel is secured a bevel-gear H, which meshes with the bevel-gear G, secured to the horizontal shaft B. By means of this connection the propeller-wheels may be revolved by rotating the shafts B. The shafts B are rotated by means of any suitable motor located within the body of the ship and connected with the shafts. This motor is shown at F. Upon the outer ends of its shaft are shown pulleys F', which carry belts F², connecting them with pulleys F³, mounted upon the shafts B.

Upon the inner ends of the sleeves C' are secured cranks C². The cranks upon the same side of the ship are connected by means of rods or bars D, so that they will all move together. The cranks upon opposite sides of the ship are connected, so as to move together, by means of a bar C³, which rigidly connects two opposite cranks or the two cranks upon one shaft. One of the cranks C² has a worm-gear E secured thereto. A worm E' is mounted upon a shaft E² and meshes with the worm-gear E. The shaft E² has a hand-wheel E³ mounted thereon, by means of which the position of the cranks may be adjusted and the position of the propeller-wheels controlled.

In rising from the ground the propeller-wheels would be adjusted horizontally unless it was desired at the same time to progress forward or to the rear. If it is desired to progress forward, the propeller-wheels are adjusted so as to face backward. If desired to progress to the rear, the propeller-wheels are turned so as to face forward. The amount of turning will seldom be sufficient to throw the propellers into a vertical plane, although this might be done in some cases. Ordinarily the propellers would be adjusted in an angular position facing to the rear and downward or to the front and downward.

Upon the upper portion of the body of the ship are two masts J. A single mast might in some cases be sufficient and answer all purposes, although two masts are preferred. In the upper portion of these masts are mounted rollers J², adapted to receive the guy-rope for controlling the air planes. Pivoted to the upper portion of the ship are two air planes I. These air planes are pivoted by their edges

which are nearest to the center of the ship, so that they may be swung upward or downward, as indicated by the solid and dotted lines in Fig. 1. A rope J' passes over the pulleys J² upon the mast and is attached to the outer edges of the body of the air planes I. The ends of the rope are then conducted into the ends of the air-ship and pass over guide-rollers J³. They are then conducted to drums K, mounted within the ship and by means of which either end may be run out or drawn in, as desired. The connection of the ends of the rope to the drums is opposite, so that when one end is drawn in the other end will be run out. By this means the air plane upon one end of the ship may be thrown downward and the air plane upon the other end thrown upward, thus placing both in the same angular position. These air planes extend beyond the sides of the ship and are to be used for controlling the vertical position of the ship. When it is desired to elevate the ship while in motion, the air planes will be thrown into such a position that their forward edges are higher than their rear edges. The forward motion of the ship will thus tend to raise it. When it is desired to descend, the air planes will be oppositely adjusted.

The drums K are operated by means of a worm-gear L, mounted upon a shaft, and turned by means of a worm L', meshing therewith and having a hand-wheel L² secured to its shaft.

The gas-chamber A' is provided with a valve M, by which a hose may be connected and the gas conducted into the same. A rudder N is pivoted to the rear end of the ship and has a handle N' extending within the ship and by which it is controlled. This rudder will provide for lateral steering of the ship.

The lower portion of the body of the ship or the lower chamber A has its bottom and side walls made water-tight for some distance upward from the bottom, so that the ship may float upon any body of water upon which it may alight.

Having thus fully described my invention, I claim as new and desire to secure by Letters Patent—

An air-ship having an air plane adapted to transverse pivots at each end of the ship, the pivot being located at the edge nearest the center of the ship, a mast between said air planes, a rope extending over the mast and attached to the outer end edges of both air planes and then extending beneath the air planes and within the body of the ship, and a drum having the ends of the rope attached thereto, and provided with means for turning whereby the planes are swung oppositely and their angular directions are maintained uniform, substantially as described.

ARISTARCHUS F. HUBBARD.
